BY Charles St. Vile ATTORNEY.

UNITED STATES PATENT OFFICE

96,019

DESIGN FOR A BOTTLE OR SIMILAR ARTICLE

Christopher J. Chamales, Chicago, Ill., assignor to C. A. Zoes Manufacturing Co., Chicago, Ill., a corporation of Illinois

Application March 7, 1935, Serial No. 55,760

Term of patent 7 years

To all whom it may concern:

Be it known that I, Christopher J. Chamales, a citizen of the United States and a resident of the city of Chicago, county of Cook and State of Illinois, have invented a new, original, and ornamental Design for a Bottle or Similar Article, of which the following is a specification, reference being had to the accompanying drawing, forming a part thereof.

On the drawing:

I claim:

The ornamental design for a bottle or similar article, as shown.

CHRISTOPHER J. CHAMALES.
